UNITED STATES PATENT OFFICE.

HENDRIK JOHAN VERSTEEG, OF DIEMEN, NETHERLANDS, ASSIGNOR TO CHRISTIAAN JOHAN JUNG, OF AMSTERDAM, NETHERLANDS.

APPARATUS FOR SPRAYING MOLTEN SUBSTANCES.

Application filed August 19, 1927, Serial No. 214,032, and in the Netherlands September 3, 1926.

This invention relates to apparatus for spraying molten substances, particularly metals such as aluminium and zinc, of the type comprising a container fitted with a nozzle through which the molten substance is ejected by air or gas under pressure, the object of the invention being to provide improved means for applying the compressed air or gas to the interior of the container.

- 10 According to the present invention a container is provided with a cover having a passage with ports at its inner and outer surfaces and a hollow lever or clip having inlet and outlet openings is arranged to exert pressure on the cover with the lever outlet registering with the outer port of the cover passage. A supply of compressed air or gas is connected to the inlet opening of the hollow lever which thus is used both to 20 conduct the compressed air or gas to the container and to close its cover.

Preferably the hollow lever bears against an adjustable stop on a projection of the container at one side of the cover and is 25 connected to the container by a resilient or nonresilient link at the other side of the cover. If desired the lever may serve as a handle for the container and its accessories. The cover may be fitted with two 30 projecting lugs between which the hollow lever may be retained by a pin engaging holes in the lugs.

The inner port of the cover passage may be protected by a plate or shield from spattering material melted inside the container.

The accompanying drawing is a sectional elevation of apparatus for spraying molten substances according to the present invention, the container 1 being heated for melting its contents or for keeping them in a molten condition by a suitable burner (not shown on the drawing) attached to a projection or the like 2. The molten contents of the container 1 are ejected through its 45 front part which is also exposed to the flame of the burner, and this part is of such shape (as illustrated) that the heat of the flame is utilized as much as possible. The flame from the burner is guided along the wall of 50 the container 1 in a passage or flue formed by a protective deflector shield 3 which also serves as a clamping piece for a nozzle 4

and a jet ring 5. The nozzle 4 is a separate part with a central bore and a faced surface around one end of that bore fitting 55 a corresponding faced edge around an opening in the container 1. At the other end of the bore the nozzle 4 is provided with a reduced portion and a tubular ring 5 fits around this reduced portion and the main 60 body of the nozzle 4. This tubular ring 5 supplies the compressed air or gas for spraying the material leaving the mouth of the nozzle 4. For this purpose perforations 6 of suitable size and shape to produce the 65 required jets of air or gas are provided in the tubular ring, and open near the mouth of the nozzle 4. The tubular jet ring 5 is connected with, and may form part of, a tube 7 for the supply of the compressed air 70 or gas.

The protective deflector shield 3 is provided with an opening to surround the perforations of the jet ring 5 and the shield acts as a clamping piece being provided 75 with screwed rods 8 disposed between lugs 9 at each side of the container 1. Nuts 10 and washers 11 are fitted to the screwed rods 8 and by screwing up these nuts 10 the protective shield 3 is drawn against the 80 tubular jet ring 5 and the latter against the nozzle 4 which is finally pressed against the container 1 so that in this manner all the parts mentioned are clamped together, and the nozzle and jet ring may be readily removed and replaced, the nozzle forming a 85 distance piece determining the width of the flue around the container provided by the shield 3.

The bore of the nozzle 4 is formed with a 90 conical portion facing inside the container 1 to form the seat for an adjusting needle valve 12 which is disposed across the container and passes through a stuffing box 13 fitted to the wall of the container opposite 95 to the nozzle 4. Means for adjusting the valve 12 are provided outside the container 1 for which purpose the needle may be screwed to engage a corresponding thread in the gland of the stuffing box 13 or in a part carried thereby, the end of the needle being 100 suitably shaped so that it may be turned by a wrench or handle in order to adjust the supply of molten material to the nozzle

4. Preferably, however, the needle 12 is adjusted by a simple axial movement.

For ejecting the contents of the container through the nozzle 4 compressed air or gas is admitted to the container 1, preferably from the same source which supplies the tube 7 and jet ring 5. For this purpose the tube 7 is fitted with a cock 14 for controlling the supply to the jet ring 5, and a branch pipe (not shown on the drawing), is coupled at 15 to the supply pipe 7 and leads to the container 1 through a hollow lever which is also used to close the cover of the container, in the following manner.

15 The container 1 is provided with a filling cover 16 which is closed by means of pressure exerted by a hollow lever 17. One end of this lever may be forked at a solid part and engages a nut 18 which is screwed to a 20 projection 19 of the container 1. The lever 17 extends across the cover 16 and on the other side thereof is connected in any suitable manner to the container 1, preferably by means of a spring 20 or other form of link 25 extending from the neck of the stuffing box 13. The lever 17 is formed with an enlargement 21 through which an outlet from the hollow interior of the lever is provided and the cover 16 is formed with a passage 22 30 having ports at its inner and outer surfaces, the parts being so disposed that the outlet of the lever 17 in the enlargement 21 registers with the outer port of the passage 22 so that the interior of the lever is connected 35 with the interior of the container. The lever is also fitted with an inlet opening at 24 to which the branch pipe leading from the supply pipe 7 at 15 is connected. In this manner compressed air or gas is conducted from the supply pipe 7 through the branch pipe, hollow lever 17, and the passage 22 of the cover 16 to the container 1. The branch pipe may be provided with a regulating valve and in the drawing a further valve 40 25 in the main supply pipe is also shown.

The outlet port of the passage 22 through the cover 16 is preferably situated between two projecting lugs 26 of the cover 16, the lever 17 being situated between the lugs 50 26. These lugs may be perforated above the lever as shown so that the latter may be retained by a pin engaging the holes.

A handle 28 may be provided on the lever 17 for holding the apparatus.

55 The inner port of the cover passage 22 is preferably protected from being obstructed by spattering material melted inside the container by a plate or shield 27 fitted to the cover.

60 What I claim is:—

1. In apparatus for spraying molten substances, the combination of a container, a cover therefor having a passage with ports at its inner and outer surfaces, a hollow lever having inlet and outlet openings, means for

enabling the lever to exert pressure on the cover with the lever outlet registering with the outer port of the cover passage and means for connecting a supply of compressed air or gas to the inlet opening of the 70 hollow lever, substantially as specified.

2. In apparatus for spraying molten substances, the combination of a container, a cover therefor having a passage with ports at its inner and outer surfaces, a hollow 75 lever having an outlet opening registering with the outer port of the cover passage, an adjustable stop on the container engaged by the lever at one side of the cover, a link connecting the lever to the container at the other side of the cover, and means for supplying compressed air or gas to the hollow lever, substantially as specified.

3. In apparatus for spraying molten substances, the combination of a container, a 85 cover therefor having a passage with ports at its inner and outer surfaces, a hollow lever having an outlet opening registering with the outer port of the cover passage, an adjustable stop on the container engaged by 90 the lever at one side of the cover, a link connecting the lever to the container at the other side of the cover, an extension of the lever beyond the link to provide a handle for the apparatus, and means for supplying 95 compressed air or gas to the hollow lever, substantially as specified.

4. In apparatus for spraying molten substances, the combination of a container, a cover therefor having a passage with ports 100 at its inner and outer surfaces, a hollow lever having inlet and outlet openings, means for enabling the lever to exert pressure on the cover between two projecting lugs thereof with the lever outlet registering with the 105 outer port of the cover passage, a pin engaging holes in the lugs and retaining the lever between the lugs, and means for connecting a supply of compressed air or gas to the inlet opening of the hollow lever, 110 substantially as specified.

5. In apparatus for spraying molten substances the combination of a container, a cover therefor having a passage with ports at its inner and outer surfaces, a plate or 115 shield protecting the inner port, a hollow lever having inlet and outlet openings, means for enabling the lever to exert pressure on the cover with the lever outlet registering with the outer port of the cover 120 passage, and means for connecting a supply of compressed air or gas to the inlet opening of the hollow lever, substantially as specified.

6. In apparatus for spraying molten substances, the combination of a container, a 125 cover therefor having a passage with ports at its inner and outer surfaces, the outer port being situated between two lugs of the cover, a plate or shield protecting the inner port, a hollow lever having an outlet 130

opening registering with the outer port of the cover passage, an adjustable stop on the container engaged by the lever at one side of the cover, a pin engaging holes in the lugs and retaining the lever between the lugs, a link connecting the lever to the container at the other side of the cover, an extension of the lever beyond the link to provide a handle for the apparatus and means for supplying compressed air or gas to the hollow lever, substantially as specified.

In testimony whereof I hereunto affix my signature.

HENDRIK JOHAN VERSTEEG.
